LEMUEL J. HATT, OF ST. LOUIS, MISSOURI, ASSIGNOR OF ONE-HALF TO FRANK P. BOYD, OF ST. LOUIS, MISSOURI.

CLAM-SHELL BUCKET.

1,097,317.

Specification of Letters Patent. Patented May 19, 1914.

Application filed April 7, 1909. Serial No. 488,508.

To all whom it may concern:

Be it known that I, LEMUEL J. HATT, a citizen of the United States, residing at the city of St. Louis, State of Missouri, have invented new and useful Improvements in Clam-Shell Buckets, of which the following is a specification, reference being had to the accompanying drawings, forming a part of this specification, in which—

10 Figure 1 is a side elevational view of my clam-shell bucket, showing the trays in closed position; Fig. 2 is an end elevational view thereof; Fig. 3 is a vertical sectional view, showing the trays in open position; Fig. 4 is a detail perspective view of one of the bottom cutting-edges or plates for the trays; Fig. 5 is a detail view of one of the side cutting-edges or plates for the trays; Fig. 6 is a top plan view of the top center 15 casting or supporting head, showing the upper sheaves or pulleys therein and the load-cable guiding sheaves; Fig. 7 is a view, slightly enlarged and partly in side elevation and partly in section, showing the guiding-plates or sheave-casing for the upper sheaves or pulleys; Fig. 8 is a perspective view of the guide-piece for the load-cable; Fig. 9 is a top plan view of the lower center casting, showing the lower sheaves or pulleys 20 therein; Fig. 10 is a vertical sectional view through the center of the casting and sheaves shown in Fig. 9; Fig. 11 is a diagrammatic plan view showing an arrangement of carriage and operating cables for my bucket; Fig. 12 is a side elevational view of the 25 parts shown in Fig. 11.

This invention relates to certain new and useful improvements in clam-shell buckets, the objects of my invention being to provide a bucket of the kind stated which will be strong, powerful, and of great efficiency, which may be operated at high-speed and in which the trays or jaws may be quickly opened and closed, and in which the load-cable is preserved and maintained in a good 40 flexible condition and wear thereon and on its coöperating sheaves or pulleys is largely reduced—substantially to a minimum, and to improve generally upon buckets of the 45 kind described.

With these objects in view, my invention consists in the novel construction of the several parts of my bucket and in the novel arrangement and combination of the same, 50 all as will hereinafter be described and afterward pointed out in the claims.

As shown in the drawings, my new bucket comprises two sections or trays 1 and 2, which are preferably built-up structures. Each of these trays comprises a bottom-plate 3 having an upturned end portion 4, the side edges or marginal portions of the plates 3 and 4 being flanged inwardly, as at 5 and 6, respectively. Flanges 5 and 6 are perforated to receive securing-rivets 7 by which side plates 8 of the trays are secured to said flanged portions 5 and 6, the side-plates 8 being also provided with registering openings or perforations for the said rivets 7. To increase the digging efficiency of the trays 70 and also the carrying capacity thereof, and as shown particularly in Fig. 1, the bottom-plate 3 of each tray is preferably inclined downwardly from its outer end inwardly and the side-plates 8 are wider at their 75 inner ends than at their outer ends.

Secured to the upper portions of side-plates 8 by a series of rivets 9 are extension-plates or arms 10, whose upper ends are pivotally mounted on studs or bolts 11 arranged on what I term the lower center casting or frame 12. Extensions or arms 10 of the said side-plates 8 are preferably reinforced by angle-braces 13, which are riveted along their outer edges, see particularly Figs. 1 and 3, by a series of rivets 14. Preferably the stiffening-braces 13 extend along nearly the entire length of the outer edges of said extensions or arms 10 and are curved at their lower ends to extend along and reinforce the upper edges of the respective side-plates 8 of said trays. Stiffening-plates 15, which extend cross-wise at the upper, outer edges of said extensions or arms 10, may also be provided, 95 the plates 15 being riveted to the flange of the stiffening-braces 13, as shown particularly in Figs. 1 and 3.

At the inner edge portions of the trays 1 and 2 are secured bottom cutting-plates 100 or edges 16, which have upturned side-portions 17 which fit against the side-plates 8 and to which they are riveted by rivets 18. This cutting-member 16 is provided with a beveled cutting-edge portion 19 and is 105 preferably recessed so as to form shoulders 20, which are adapted to abut against the front edges of the bottom and side-plates 3 and 8, respectively. The side-portions 17 of this cutting member 16 do not extend up 110 the entire face of the side-plates 8, as shown particularly in Figs. 1 and 3, separate side-

plates 21 being preferably provided, which form substantially a continuation of said side-portions 17. These plates 21 are also provided with cutting-edges 22 and recessed portions which form shoulders 23, similar to 5 said shoulders 20 of said cutting-member 16, the plates 21 being also adapted to be secured in position by suitable rivets. As is obvious, should these cutting-members 10 become worn by use, new cutting-members may be easily and readily substituted therefor.

At the upper rear portion of each tray are 15 secured lugs or ears 25, which are perforated to receive suitable pivot bolts or pins 24 upon which the lower ends of links or bars 26 are pivotally mounted. Preferably each tray-section is provided with two pairs of 20 these links or bars 26, whose lower ends are spread apart or diverge, substantially as shown in Fig. 2, the upper ends thereof being brought together and pivotally mounted or secured on bolts or pins 27 secured in lugs or ears 28 formed upon what I term 25 the upper center casting or supporting-head 29. The casting or head 29 is provided, as shown particularly in Fig. 6, with vertical bores 30 at both ends, and in these bores are suitably fastened depending guide-members, preferably rods, 31, said rods 31 being secured in said bores in any suitable manner, preferably by means of collars 32 on the upper ends thereof and adapted to abut against the top of said casting 29 30 and the pins 32' passing through said casting and said rods. The rods 31 extend downwardly in parallel relation for a suitable distance between the respective links 26 connecting the respective trays 1 and 2 to 35 said casting or head 29 and have on their lower ends heads or collars 33, which collars 33 are adapted to limit the lowermost position of the lower casting 12, the casting 12 being provided with vertically bored portions or sleeves 34, see particularly Figs. 9 and 10, which are adapted to slidably fit 40 on said rods 31, for purposes more fully hereinafter appearing.

Casting or frame 12 is preferably a 50 comparatively heavy box-like receptacle having a rounded bottom 35, in which receptacle is adapted to be received and held a lubricant or oil, for purposes hereinafter more fully set forth, the said casting being provided on its sides with suitable stiffening ribs or webs 36 and with bosses 37, in which bosses the pivot studs or pins 11 for the extensions or arms 10 are fitted. Bottom 35 of said casting is preferably provided with a threaded opening in which a threaded plug 35' is 55 adapted to fit, whereby the oil or other lubricant therein may be drained therefrom whenever desired.

Rotatably mounted on a shaft 38, which 60 shaft is fixedly mounted in the sides, and

extends across the center portion, of casting 12, see particularly Fig. 9, is a series of independent grooved pulleys or sheaves 39, 39', and 39''. A sheave-casing comprising a plurality of walls or plates 40 suitably bored 70 to accommodate and provide a bearing centrally, so to speak, for said shaft 38, is preferably secured within said casting or frame 12, said plates or walls being between the said respective pulleys and between the 75 outermost pulleys and the sides of said casting or frame, whereby the load-cable L is guided within said frame and prevented from slipping out of the grooves of said respective pulleys. As shown particularly 80 in Figs. 9 and 10, the innermost plates 40 are preferably flanged outwardly and suitably connected at their ends to end-plates 41, forming divisions in said casing within which said respective sheaves are mounted, 85 as stated. Said end-plates 41 are also flanged outwardly at their ends, as at 42, and perforated to receive bolts or rivets 43, these rivets 43 also passing through outermost plates 40 and frame 12, whereby said 90 casing is secured in place.

The middle portion of the upper casting 29 is diagonally arranged with respect to the top of the lower casting 12 and is provided with an elongated opening 44, in 95 which a series of grooved pulleys or sheaves 45, 45', and 45'' are loosely mounted and independently rotatable on a shaft 46 fixedly mounted in said casting or head 29. A sheave-casing somewhat similar to the 100 sheave-casing provided around said lower sheaves is also provided in said opening 44 and around said upper sheaves. This casing likewise comprises a plurality of walls or plates 47 suitably bored to accommodate, 105 and provide a bearing centrally, so to speak, for said shaft 46, the two intermediate plates dividing said casing into divisions within which said upper sheaves are, respectively, arranged and being flanged at 110 their ends and suitably attached or secured to the bent ends of the two outermost plates substantially as shown in Fig. 6, and the ends of said outermost plates being brought together, as at 48, where they are riveted 115 or otherwise secured together and to the side members 49 of said casting or head 29.

Swiveled in vertically bored portions 50 at diagonally opposite points on the casting 29 are tubular pulley-supporting members 51, said members 51 being provided with wings 52, in which are journaled grooved pulleys or idlers 53. Preferably these tubular pulley-supports 51 have collars 54 at their upper and lower ends, which serve to prevent them from moving endwise in the bored portions 50, but permit the same to rotate freely therein. The pulleys 53 are arranged in pairs with their peripheral portions in close relation, see particularly Fig. 6, where- 125 130

by these pulleys serve as anti-friction guides for the load-cable L, which passes therebetween. Pulleys 53 are arranged vertically in coöperative relation to the two outer sheaves 39 and 39" in the lower casting, and the two outer sheaves 45 and 45" in the upper casting 29 are likewise arranged diagonally in coöperative alinement or relation with the said sheaves 39, 39', and 39" in the lower casting 12, as shown particularly in Fig. 3, the center sheave 45' of the set of sheaves in said upper casting 29 being provided for the supporting-cable S for supporting the bucket and holding the same in its various raised or lowered positions during the use or operation thereof. As shown in Fig. 7, I preferably provide on said upper casting 29 a guide-piece 55 for the cable S, which guide-piece is adapted to fit between the two intermediate plates 47, these plates extending slightly above the two outermost plates of said sheave-casing or guide-frame. The guide-piece 55 is provided with holes or perforations 56 near both ends thereof, which holes are located in vertical coöperative relation or alinement with the groove in the middle sheave 45' and through which said cable S is adapted to pass. Guide-piece 55 is also provided with lugs 57, which are perforated laterally, as at 58, to receive bolts 59 for securing said guide-piece in position.

In practice, the bucket is usually supported from a carriage 60 movable on a run-way or track 61, the carriage being operated or moved by a cable 62, which is substantially an endless-belt arrangement operated from a suitable drum in a well-understood manner. And, in practice, the supporting-cable S is adapted to be fastened at one end to some suitable fixed point preferably on the run-way or track 61, is then passed over a sheave 33 on the carriage 60, then down through one of the openings 56 in the guide-piece 55, thence under sheave 45' in upper casting 29, then up through the opposite opening or hole 56 in said guide-piece 55, over another sheave 64 on said carriage 60, and then over a suitable idler sheave 65 on the said run-way or track 61 to a suitable winding drum in an ordinary manner. Also in practice, the load-cable L is adapted to be fastened at one end to some suitable fixed point preferably on the run-way or track 61, is then passed over a sheave 66 on the carriage 60, then down between one pair of guide-pulleys 53, then through the tubular swivel support 51 therefor, then under one of the outermost sheaves, say 39, in the lower casting 12, then up and over the coöperating sheave 45 in the upper casting 29, then down and under sheave 39', then up and over sheave 45", then down and under sheave 39", then up and through the tubular swivel support 51 for the opposite pair of guide-pulleys 53, then between said last-named pair of guide-

pulleys 53, then over a sheave 67 on the carriage 60, and then over a suitable idler sheave 68 on the track or run-way 61 to a suitable winding-drum (not shown). The arrangement of the sheaves 39, 39', 39", 45, 45" and the winding of the load-cable L therearound provides substantially a block-and-tackle well adapted for opening and closing the trays of my bucket during the use or operation thereof and one which I have found particularly well adapted for such purpose, and while I have shown and described five sheaves in this block-and-tackle, it is obvious that a greater or less number of sheaves might be employed, as desired, depending upon the weight of the bucket and the load to be carried thereby.

In operation, as is obvious, by means of cable 62 the carriage 60 may be moved to any position on track or run-way 61, as desired, while by means of supporting-cable S the bucket, with the trays 1 and 2 either in closed or open position, depending upon the winding of the load-cable L on its winding-drum, may be held in various raised or lowered positions relative to said track or run-way 61. In Figs. 1 and 2, I have shown the trays in closed position, the lower casting 12 with the sheaves 39, 39', and 39" being in close proximity to upper casting 29 and held in such position by cable L, cable L being tightly wound upon its winding-drum. To open said trays, cable L is released or unwound, when sheaves 39, 39', and 39" will drop by gravity, the trays 1 and 2 opening. This opening is, however, somewhat slow, and to accelerate the opening of said trays the casting or frame 12 is made comparatively heavy, the weight thereof tending to more quickly draw said sheaves downwardly and force said trays into open position; the downward movement of said sheaves and said casting being limited by the collars 33 on the lower ends of rods 31, upon which rods said casting slides. In Fig. 3 the trays are shown in full open position, and in which position, it will be seen that said trays are particularly well adapted for digging into the sand, gravel, ore, or other material being operated upon, and the said casting, until the same is drawn upwardly by the winding of cable L upon its winding-drum, tends to keep said trays in this open position. The supporting-cable S being free to unwind from its winding-drum, so that the bucket may bodily drop, my bucket, due partly to the weight of the trays and the weight of said casting and associated parts, will readily dig into the sand, gravel, ore, or other material upon which the bucket is being used, my bucket being better adapted for such purpose than any other bucket with which I am familiar. Should the cutting edges 16 or 21 become worn, they may be easily replaced, as is obvious. When the

casting 12 with said carried sheaves is drawn upwardly by the winding of cable L on its winding-drum, the trays 1 and 2 will be brought to closed position, during this closing operation said trays readily scooping up the sand, gravel, ore, or other material being operated upon, the bucket, with said trays in open or closed position, as before described, being held in any raised or lowered position relative to said carriage by means of said supporting-cable S. As is obvious and as before stated, the said carriage upon which the bucket is mounted may be moved to any position desired on said runway or track 61 by means of said cable 62.

In order to preserve cable L and prevent all undue wear thereof, and at the same time to keep said sheaves 39, 39', and 39'' well lubricated, so that they may freely rotate and without unnecessary friction, I fill casting 12 with a suitable lubricant, which not only thoroughly lubricates said sheaves, but also, so to speak, permeates said cable, thereby preventing all undue inside and outside wear of the strands thereof and keeps the same flexible. I have found that in buckets now on the market and of which I am aware the inner and outer strands of the load-cable very rapidly wear, necessitating frequent renewals of the cable; in my bucket, however, the life of the cable is not only increased, but the cable is kept in good flexible condition and the closing and opening movements of the trays 1 and 2 are freer and easier on the winding and unwinding of said cable L on its winding-drum. As is obvious, by removing plug 35', the casting 12 may be drained and cleaned, whenever necessary, and replenished with a fresh supply of lubricant, plug 35', of course, again closing its coöperating opening in the bottom of said casting. By arranging the sheaves in the upper casting diagonally in coöperative alinement or relation with the sheaves in the lower casting, there is less torsional or twisting strain on the cables than where the sheaves in the upper casting are arranged vertically in coöperative alinement or relation with the sheaves in the lower casting, and in my bucket, through the means heretofore described, there is very little, if any, liability of the cables slipping out of the grooves of the respective sheaves, thus avoiding any unnecessary stoppage of the operation of the bucket and unnecessary wear and tear upon the cables and sheaves. And by mounting the guide-pulleys 53 upon supports free to rotate, not only may the bucket swing and turn relative to its supporting-carriage without disarranging the operating cables therefor, but unnecessary friction and consequent wear upon said cables during such twisting or turning movements of the bucket are obviated. By mounting and arranging the

sheaves in the upper and lower castings so that the same are independently rotatable, the opening and closing movements of the trays 1 and 2 are facilitated; and by making said sheaves comparatively heavy, wide, and large, not only is the digging efficiency of the bucket increased, but the wear on said sheaves and on their supporting shafts is greatly reduced.

In Figs. 11 and 12, I have shown diagrammatically, for the purpose of more fully explaining the use and operation of my bucket, the manner in which I prefer to mount my bucket on a supporting-carriage and to arrange its operating-cables, this arrangement of said cable and the mounting of said bucket possessing many obvious advantages not heretofore attained; but it is to be understood that my bucket might be mounted and its operating-cables arranged in other ways, and that many minor changes in the construction, arrangement, and combination of the several parts of my bucket might be made and substituted for those herein shown and described without departing from the nature and spirit of my invention.

Having thus described my invention, what I claim and desire to secure by Letters Patent is:

1. A bucket of the kind described comprising a supporting-head provided centrally with a diagonally-disposed opening, a set of sheaves rotatably arranged in said opening, coöperating load-trays, links pivotally connected to said head at the ends thereof and to said trays, rods depending from said head between said links and at opposite ends of said diagonally-disposed opening, a box-shaped sheave-frame provided with portions fitting on said rods, a set of sheaves rotatably mounted in said frame, said head-sheaves being diagonally disposed in coöperative vertical relation to said frame-sheaves, arms mounted on said trays and pivotally connected to said frame, and flexible means adapted to coöperate with said sets of sheaves to open and close said trays, said frame being adapted to slide on said rods on the opening and closing of said trays; substantially as described.

2. A bucket of the kind described comprising a supporting-head, sheaves rotatably mounted in said head, coöperating load-trays, diverging pairs of links pivotally connected at their opposite ends to said head and to said trays, guide-members depending from said head, a sheave-frame having portions fitting on said guide-members, sheaves rotatably mounted in said frame, side arms rigidly secured to said trays and pivotally connected to said frame, brace-members connecting said arms, and flexible means adapted to coöperate with said head- and frame-sheaves to open and close said trays, said frame being adapted to slide on said guide-

members on the opening and closing of said trays; substantially as described.

3. A bucket of the kind described comprising a supporting-head, sheaves rotatably mounted in said head, coöperating load-trays, diverging pairs of links pivotally connected at their opposite ends to said head and to said trays, rods depending from said head and having their lower ends free, a sheave-frame slidably mounted on said rods, sheaves rotatably mounted in said frame, arms rigidly secured to said trays and pivotally connected to said frame, brace-members connecting said arms, and flexible means adapted to coöperate with said head and frame sheaves to open and close said trays, said frame being adapted to slide on said rods on the opening and closing of said trays; substantially as described.

20 4. The combination with a supporting-cable, of a bucket of the kind described, the same comprising a supporting-head provided centrally with an enlarged opening, a supporting-sheave around which said cable is adapted to pass rotatably mounted in said opening, tray-operating sheaves also rotatably mounted in said opening, coöperating load-trays, links pivotally connected to said head at the ends thereof and to said trays, rods depending in parallel relation from said head at opposite ends of said enlarged opening and between said links, a sheave-frame having portions fitting on said rods, tray-operating sheaves rotatably mounted in said frame, arms on said trays pivotally connected to said frame, and flexible means adapted to coöperate with said tray-operating sheaves to open and close said trays, said frame being adapted to slide on said rods on the opening and closing of said trays; substantially as described.

5. The combination, in a bucket of the kind described, with a supporting-head having an opening therein, of a sheave casing arranged within said opening and secured to said head, bored walls dividing said casing and secured at their ends to the ends of said casing, a shaft mounted in said head and passing through said head, casing, and walls, and sheaves rotatably mounted on said shaft within the divisions formed by said walls; substantially as described.

6. The combination, in a bucket of the kind described, with a supporting-head having an opening therein, of a sheave casing arranged within said opening and secured to said head, said casing comprising side walls and intermediate walls, said side walls being bent at opposite ends and secured together and to said casing and said intermediate walls dividing the space between said side walls into divisions and being secured at their ends to said end walls, a shaft mounted in said frame and passing through said side and intermediate walls, and sheaves rotatably mounted on said shaft within the divisions formed by said intermediate walls; substantially as described.

bent ends of said side walls, a shaft mounted in said head and passing through said head and walls, and sheaves rotatably mounted 65 on said shaft within the divisions formed by said intermediate walls; substantially as described.

7. The combination, in a bucket of the kind described, with a supporting-head having an opening therein, of a sheave casing arranged within said opening and secured to said head, said casing comprising side walls and intermediate walls, said intermediate walls dividing the space between said 75 side walls into central and outer divisions, a shaft mounted in said head and passing through said walls, a bucket-supporting sheave rotatably mounted on said shaft within said central division, and tray-operating sheaves rotatably mounted on said shaft within said outer divisions; substantially as described.

8. The combination, in a bucket of the kind described, with a supporting-head having an opening therein, of a sheave-casing arranged within said opening and secured to said head, said casing comprising side walls and intermediate walls, said intermediate walls dividing the space between said side 90 walls into central and outer divisions, a shaft mounted in said head and passing through said head and walls, a bucket-supporting sheave rotatably mounted on said shaft within said central division, tray-operating sheaves rotatably mounted on said shaft within said outer sheaves, and a perforated cable-guiding member secured to said intermediate walls above said bucket-supporting sheave; substantially as described.

9. The combination with a bucket of the kind described having a lower sheave-frame, of a sheave casing arranged in and secured to said frame, said casing comprising side 105 walls, end walls, and intermediate walls, said side and end walls being secured together and to said frame and said intermediate walls dividing the space between said side walls into divisions and being secured at 110 their ends to said end walls, a shaft mounted in said frame and passing through said side and intermediate walls, and sheaves rotatably mounted on said shaft within the divisions formed by said intermediate walls; substantially as described.

In testimony whereof, I have signed my name to this specification in the presence of two subscribing witnesses.

LEMUÉL J. HATT.
